CLAIM

The ornamental design for a lid as shown and described.

DESCRIPTION

FIG. 1 is a top perspective view of my new design for a lid with a closure in a closed position;

FIG. 2 is a bottom perspective view thereof;

FIG. 3 is a top plan view thereof;

FIG. 4 is a front side elevation view thereof;

FIG. 5 is a bottom plan view thereof;

FIG. 6 is a cross-sectional right side elevation view thereof along axis **6-6** of FIG. 3;

FIG. 7 is a top perspective view with the closure rotated 180 degrees from that shown in FIG. 1;

FIG. 8 is a bottom perspective view of the lid of FIG. 7;

FIG. 9 is a top plan view of the lid of FIG. 7;

FIG. 10 is a front side elevation view of the lid of FIG. 7;

FIG. 11 is a bottom plan view of the lid of FIG. 7;

FIG. 12 is a cross-sectional right side elevation view of the lid plug along axis **12-12** of FIG. 6;

FIG. 13 is a top perspective view of the lid with the closure rotated at 90 degrees from that shown in FIG. 1; and,

FIG. 14 is the top perspective view of the lid of FIG. 1 as shown with an exemplary cup in broken lines.

Portions of a cup shown in broken lines in FIG. 14 form no part of the claimed design and illustrate an exemplary environment of the lid.

1 Claim, 7 Drawing Sheets
